(57) **CLAIM**

The ornamental design for a troffer light, as shown and described.

DESCRIPTION

FIG. 1 is a perspective view of the front of a troffer light showing my new design;

FIG. 2 is a front elevational view of the troffer light of FIG. 1;

FIG. 3 is a rear elevational view of the troffer light of FIG. 1;

FIG. 4 is a left side elevational view of the troffer light of FIG. 1;

FIG. 5 is a right side elevational view of the troffer light of FIG. 1;

FIG. 6 is a top plan view of the troffer light of FIG. 1;

FIG. 7 is a bottom plan view of the troffer light of FIG. 1;

FIG. 8 is an exploded view of the light frame of the troffer light taken from the circled portion in FIG. 1; and,

FIG. 9 is a perspective view of the rear of a troffer light showing my new design.

The broken lines in the drawings illustrate the environment of the troffer light and form no part of the claimed design.
